UNITED STATES PATENT OFFICE.

HENRY A. CARPENTER, ROBERT L. HIBBARD, AND ARTHUR W. WARNER, OF SEWICKLEY, PENNSYLVANIA, ASSIGNORS TO RITER-CONLEY MANUFACTURING COMPANY, OF PITTSBURGH, PENNSYLVANIA, A CORPORATION OF NEW JERSEY.

APPARATUS FOR CHARGING AND DISCHARGING GAS-RETORTS.

1,144,166.

Specification of Letters Patent. Patented June 22, 1915.

Application filed February 15, 1913. Serial No. 748,643.

To all whom it may concern:

Be it known that we, HENRY A. CARPENTER, ROBERT L. HIBBARD, and ARTHUR W. WARNER, citizens of the United States, residing at 5 Sewickley, in the county of Allegheny and State of Pennsylvania, have invented certain new and useful Improvements in Apparatus for Charging and Discharging Gas-Retorts, of which the following is a specification.

Our invention relates to improvements in apparatus for charging and discharging gas retorts, and particularly to apparatus of the character shown and described in a 15 pending application Serial Number 530,883 filed November 29, 1909.

Among the objects of the present invention are: to provide means for shaping or leveling the coal contained in the charger and discharger to prevent the contents of the charger and discharger from striking the upper edge of the mouth of a retort and being thrown into the retort house; positively operable means for actuating the shaper; 25 means for supporting the charger and discharger located at the forward end of the apparatus; means for adjusting the shaper to desired positions relatively to the charge of coal being introduced to a retort; buffering means located at the forward end of the apparatus adapted to make contact with a horizontally movable carriage on which the combined charger and discharger is carried; and a new and improved combined charger 30 and discharger.

In the accompanying drawings which illustrate an application of our invention: Figure 1 is a part side elevational view and a part sectional view of the forward end of 40 the charging and discharging apparatus; Fig. 2 is a part elevational view and a part sectional view of the same, the section being taken on line II-II of Fig. 3; Fig. 3 is a part front elevational view and a part 45 sectional view of the forward end of the apparatus; Fig. 4 is a sectional view of the forward end of the charger and discharger members, the section being taken on line IV-IV of Fig. 5 looking in the direction 50 of the arrows; and Fig. 5 is a front view of the forward end of one of the chargers and dischargers.

As illustrated and as preferred, the com-

bined charger and discharger 2 are mounted on a horizontally movable carriage 3, said carriage being supported on ways 4 by means of rollers or wheels 5 and 6, the wheels 5 being mounted on the upper faces of the ways 4, and the wheels 6 being designed to make contact with the underside 60 of said ways 4.

The carriage, together with the charger and discharger, are adapted to be moved forward and backward by means of a rotative screw member 7 projecting through a 65 nut 8 depending from the carriage. The horizontally movable carriage and the mechanism for moving it form no part of the present invention, said carriage and mechanism being described and shown in the pending application aforesaid, and it is deemed unnecessary to further describe the same in this specification.

The means for shaping the charge of coal contained in the charger and discharger, as 75 illustrated, include a roller member 9 mounted on a shaft 10, which shaft has its bearings in members 11 supported by and movable with a movable frame 12. Frame 12 is mounted on a shaft 13, the latter having 80 its ends supported by brackets 14 projected outwardly from a plate secured to a transversely extending girder 15, the latter being carried on the charging and discharging apparatus.

The frame 12 carrying the roller 9 may be moved toward or away from the combined charger and discharger, and for this purpose we provide an adjusting screw 16 extended through a member 17, as particularly shown by Fig. 2. The roller shaper or leveler 9 is preferably of the form shown, and is designed to be rotated at substantially the same rate of speed as the movable carriage is driven by the driving screw 7, and 90 for this purpose, we have provided positively operable means, said means being connected with the driving screw 7 and actuated thereby.

The positively operable means as shown 100 include a gear wheel 20 mounted on the forward end of the driving screw 7, a gear 21 located below said gear 20 and adapted to mesh therewith, a shaft 22 on which the gear 21 is mounted, a bevel gear 23 secured to the 105 opposite end of shaft 22, a bevel wheel 24,

the latter being mounted on one end of a laterally extending shaft 25, which latter shaft has secured on its opposite end, a bevel gear 26. In addition to the parts mentioned, this driving mechanism includes a vertically disposed driving rod 27 having at its lower end a gear 28 adapted to mesh with the gear 26; horizontally disposed shaft 13 has a bevel gear 30 mounted on an end thereof, said gear 30 being designed to mesh with a gear 31 carried on the upper end of the vertically extending shaft 27. On the opposite end of shaft 13, we provide a gear wheel 32 which wheel meshes with a large wheel 33 mounted on an end of the roller shaft 10.

A mouth of a horizontally disposed retort is indicated by the numeral 34, and the position of the charge contained in the charger and discharger is indicated by the dotted line 35. The manner of depressing or leveling the charge preliminary to its introduction into the retort so as to prevent the upper surface of the charge from striking the retort opening is particularly shown by Fig. 3.

The means employed for supporting the charger and discharger include rollers 36 disposed preferably directly under the lever 9 and on opposite sides of the charger and discharger, said rollers being supported from a plate member 37 located at the forward end of the apparatus. These rollers have their axes relatively inclined in such manner as to afford a support against sagging both in vertical and lateral directions.

Located on opposite sides of the apparatus and at the forward end thereof, we provide buffering or shock absorbing springs 38 designed to make contact with the respective wheels 5 of the carriage as the carriage reaches the limit of its forward movement.

Fig. 4 of the drawings particularly shows the forward ends of a pair of scoops constituting the charger and discharger. As shown herein, and as more particularly described in the pending application above mentioned, the charger and discharger comprises a pair of scoops or trough-shaped members, with each scoop or member including an outer member *a* and an inner member *b*. In the new form of charger and discharger as shown by Fig. 4, the outer members *a* are each provided with a projecting member *c*, said member *c* having a head *d* formed with a curved slit *e*. Each of the inner members *b* are also provided with a projecting end portion *f*, and the outer ends of the portions *f* are respectively designed to be entered in the respective slits of the heads *d*. This particular arrangement of the forward ends of the scoops is of particular advantage in connection with rollers 36. As will be seen the heads *d* act somewhat as guides for the members *b*

(through their continuations *f*), so that when the scoops are projected and given their turning movements, the weight of the projected portions of the scoops together with the weight of the coal carried thereby 70 will not be effective to cause a disarrangement of the scoop members at such end, each scoop member retaining its individuality in this respect, and the rollers 36, during the movement of the scoops into their forward 75 positions, preventing lateral sagging of the scoops relative to each other, thus tending to prevent the charge from being dropped between the scoops while passing to charging position.

What we claim is:—

1. In an apparatus for charging gas-retorts, a horizontally movable charger, and rotary means for shaping the coal contained in the charger prior to the introduction of the latter into and during its movement to charge the retort.

2. In an apparatus for charging and discharging gas-retorts, a horizontally movable charger, rotary means for shaping the coal contained in the charger during the movement of the latter to charge the retort, and positively operable means for actuating the shaping means.

3. In an apparatus for charging and discharging gas-retorts, a horizontally movable charger, rotative means for moving the charger, a roller for shaping the coal contained in the charger, and positively operable means for rotating the roller, said roller rotating means being actuated by the means for moving the charger.

4. In an apparatus for charging and discharging gas-retorts, a horizontally movable charger, rotative means for moving the charger, a roller for shaping the coal contained in the charger during the movements of said rotative means, means for adjusting the roller relatively to the charger, and positively operable means for rotating the roller.

5. In an apparatus for charging and discharging gas-retorts, a horizontally movable charger, rotative means for moving the charger, a roller for shaping the coal contained in the charger, means for adjusting the roller relatively to the charger, and positively operable means for rotating the roller, said roller rotating means being actuated by the means for moving the charger.

6. In an apparatus for charging and discharging gas-retorts, a horizontally movable charger adapted to convey a charge of coal to a retort, rotative means for moving the charger, a roller for leveling the coal in 125 the charger during its travel toward the retort, charger supporting rollers, and positively operable means for rotating the coal leveling roller, said latter means being actuated by the means for moving the charger.

7. In an apparatus for charging gas retorts, a longitudinally movable charger, and means traversed by the charger for shaping the coal contained in the charger during its movement in one direction prior to its introduction into the retort. 20
8. In an apparatus for charging gas retorts, a longitudinally movable charger, and rotary means traversed by the charger for shaping the coal contained in the charger during its movement in one direction prior to its introduction into the retort. 25
9. In an apparatus for charging gas retorts, a longitudinally movable charger, rotary means traversed by the charger for shaping the coal contained in the charger prior to its introduction into the retort, and means for maintaining a definite relation between the speed of the rotary means and the speed of the charger. 20
10. In an apparatus for charging gas retorts, a longitudinally movable charger, rotary means traversed by the charger for shaping the coal contained in the charger prior to its introduction into the retort, and means for rotating the rotary means at the same speed as the speed at which the charger travels. 25

In testimony whereof we affix our signatures in presence of two witnesses.

HENRY A. CARPENTER.
ROBERT L. HIBBARD.
ARTHUR W. WARNER.
